UNITED STATES PATENT OFFICE

LELAND S. ROSENER, OF SAN FRANCISCO, CALIFORNIA, ASSIGNOR TO THE PARAFFINE COMPANIES, INC., OF SAN FRANCISCO, CALIFORNIA, A CORPORATION OF DELAWARE

APPARATUS FOR HANDLING SHEETS

Application filed April 6, 1931, Serial No. 528,222.

My invention relates to apparatus for handling sheets, and particularly to such apparatus for handling long sheets of material, such as webs of printed floor covering.

5 It is among the objects of my invention to provide an apparatus for efficiently and easily handling the long, heavy and cumbersome webs of floor covering as they are drawn from the drying racks for inspection and 10 cutting up into rug lengths.

Further objects of my invention include the provision, in an apparatus of the character described, of means for handling the sheets whereby each may be operated on at substantially the same level as the rack from which the sheet is being withdrawn, so that stresses imparted by the passing of the sheet from one level to another are avoided; and of means for advancing the sheet along the operating station, which means also operates to pull the sheet from its rack, so that the withdrawal of a sheet from its rack ceases when the advance of the sheet along the operating station is stopped; this latter action thus being effected without the inclusion of numerous mechanisms, timing devices and controls.

The invention possesses other objects and features of advantage, some of which, with the foregoing, will be set forth in the following description of my invention. It is to be understood that I do not limit myself to this disclosure of species of my invention, as I may adopt variant embodiments thereof within the scope of the claims.

35 Referring to the drawings:

Figure 1 is a side view, partly in section and partly in elevation, showing the apparatus embodying my invention, together with portions of the building in which it is housed.

40 Portions of the view, in both vertical and longitudinal directions, are omitted to reduce its size, since the apparatus as actually installed is of very large proportions. For example, the height of the hauling-in mechanism, as shown in the upper left hand portions of the view, above the ground floor in the installation now being described, is around fifty feet.

45 Figure 2 is a vertical sectional view of the apparatus embodying my invention, taken

in a plane indicated by the line 2—2 of Figure 1.

Figure 3 is a plan view of the mechanism for starting the pulling-out operation; and

55 Figure 4 is a side elevation of the same with portions shown in section to illustrate the construction more clearly.

Figure 5 is a vertical sectional view showing the drive mechanism, taken in a plane indicated by the line 5—5 of Figure 4.

60

In terms of broad inclusion, the apparatus embodying my invention comprises a plurality of tiers of racks, each rack comprising a support adapted to hold a long, heavy web of wet printed floor covering during the period necessary for it to dry. Means, transversely movable across the discharge ends of the plurality of tiers of racks, are provided for hauling the webs of floor covering onto selected racks as they leave the printing machine; this hauling-in mechanism also including vertically adjustable means for positioning the hauling-in cable opposite a selected rack.

70 A main frame mounted for movement across the end of the tiers is provided, and means are provided for moving the frame to position the same opposite a selected tier. A frame slidably arranged on the main frame is also provided, and means are provided for moving the slidable frame to a position opposite a selected rack. An elongated table is arranged on the slidable frame, and a conveyor, preferably an endless belt conveyor, is mounted on the table.

75

80 Means are provided for pulling a portion of the sheet out of the rack and depositing it on the conveyor belt, the amount of sheet pulled out by the pulling-out means being such that the frictional engagement of the sheet with the conveyor operates to continue pulling out the sheet. As the sheet is moved along the table by the conveyor it may be inspected and cut up into rug lengths. A winder is arranged on the slidable frame for 85 rolling up the rugs as they pass from the table, and means are provided for lowering the rug rolls from the slidable frame.

90 In greater detail, and referring particularly to Figure 1, the apparatus embodying my

85

90

95

100

invention is housed in a building of which portions of the floor 2 and super-structure 3 are shown. Arranged in the building are a plurality of tiers of racks, one tier of which is shown at the left in Figure 1, for holding the sheets to be handled. In the present embodiment of my invention the racks serve to hold long sheets or webs of freshly printed floor covering for drying purposes. The machine for printing the sheets of floor covering is not shown, suffice to say that it is preferably mounted for movement across the receiving end of the tiers of racks, so that it may be positioned in front of the tier into which the sheet is drawn as it is printed.

The tiers of racks are preferably separated by narrow passageways thru which workmen may pass, and each tier is built up of the vertical supporting standards 4, spaced at suitable intervals lengthwise of the tier; the corresponding standards at each side being connected by the rods 6 extending transversely across the tier. Resting on the rods 6 are suitable flat strips 7 extending the entire length of the tier and spaced apart at suitable intervals transversely of the tier to provide a support upon which the long webs of printed floor coverings may rest while drying. The rods 6 are spaced but a few inches apart and each tier extends upwardly for more than forty feet above the floor, so that in the aggregate a large number of individual racks are provided.

Means are provided for drawing a web into a selected rack as it leaves the printing machine. This hauling-in mechanism is preferably similar to that described in detail in my Patent No. 1,743,397, issued January 14, 1930. In view of this previous disclosure the present mechanism will not be dealt with in detail, suffice to say that it comprises a frame 8 mounted for movement across the end of the tiers of racks. Mounted on top of the frame 8 is the cable hauling mechanism 9 for drawing a freshly printed sheet 11 into one of the racks. The cable 12 has one end wound around a drum 13 of the hauling mechanism 9, and is secured at the other end to the sheet 11 by a suitable clamp 14. The cable 12 is positioned opposite a selected rack by means of the vertically movable sheave 16.

As set forth in my patent above referred to, two hauling-in cables are preferably provided, so that no time need be lost in starting the leading end of the next sheet into its rack. When a length of web sufficient to fill a rack has been printed the web is severed at the printing machine. The leading end of the sheet is then perhaps forty feet from the discharge end of the rack. The hauling in continues, and meanwhile the other hauling-in cable is connected to the leading end of the next succeeding sheet, consequently the printing continues without loss of time. After a sheet has been hauled into position in the

rack, with its leading end projecting a few inches from the discharge end thereof, the clamp 14 is detached and carried back to the receiving end of the racks by a workman operating in one of the passages separating the tiers.

Thus the hauling in of the sheets continues until the racks are filled, it being contemplated that by the time the tiers are filled the first printed sheets will have sufficiently dried to permit their removal. Means are therefore provided for pulling the dry sheets out of the racks and moving them past an operating station for inspection and cutting up into rug lengths. This pulling-out operation comprises pulling a portion of the sheet out of its rack and depositing it on a conveyor extending along the operating station; the amount of the sheet pulled out being such that the frictional engagement of the sheet with the conveyor operates to continue pulling the sheet out of the rack.

Arranged adjacent the structure comprising the hauling-in mechanism is a generally rectangular main frame built up of the vertical columns 17 connected at their tops and bottoms by the tie beams 18. The frame preferably has a width substantially equal to the width of a tier of racks, and is mounted for travel across the end of the tiers, so that it may be positioned opposite a selected tier. Suitable grooved rollers 19 adapted to run on the rails 21 allow the main frame to move across the end of the tiers, and a motor 22 driving thru suitable reduction gears 23 serves to drive the frame along the rails.

Slidably mounted in the main frame is a second frame comprising a platform 24 which is adapted to move up and down; viz, the platform 24 operates as an elevator in connection with which the main frame serves as the shaft. The platform is supported by a plurality of cables 26 wound about the drums 27 arranged along the shafts 28. Connected with each of the drums 27 is a second drum 29 about which is wrapped a cable 31 suspending a counterweight 32. Suitable sheaves 33 serve to hold the counterweights 32 clear of the main frame.

Suitable reduction gearing 34 connect the drum shafts 28 with a cross shaft 36, which in turn is driven by a motor 37 thru suitable gearing 38. By this arrangement the platform 24 may readily be raised or lowered to a position opposite a selected rack. The platform 24 extends along the length of the main frame so that it projects for a distance beyond each end of the main frame. An elongated inspection table 39 is arranged on the platform 24 and extends from the forward end of the platform to a point spaced from the rear end thereof. The sides of the table 39 are spaced inwardly from the sides of the platform to provide a passageway for workmen, and suitable side rails 41 are pro-

vided along the side edges of the platform for the safety of workmen.

Means are provided for pulling a portion of a dried sheet 42 out of its rack and depositing it on the forward or receiving end of the inspection table 39. To this end an arm 43 of open framework construction is movably mounted on the forward end of the table 39. As best shown in Figures 3, 4 and 5, an apron 44 projects downwardly from each side of the arm 43, and each apron carries a pair of rollers 46 engaging suitable guide ways 47 along the sides of the table 39. Each apron also carries a pinion 48 meshed with a rack 49 arranged along the side of the table; the pinion 48 being driven by a motor 51 thru suitable reduction gearing 52. The motor 51 is mounted on a base plate 53 secured to the framework of the arm 43, and is connected directly to one of the reduction gears 52, while a shaft 54 extending across the arm 43 serves to complete the drive to the other reduction gearing.

When the arm carriage just described is at the extreme forward end of the table 39, the arm 43 projects beyond the table to a point adjacent the racks, as is best seen in Figure 1. Referring particularly to Figures 1, 3 and 4, the forward or projecting end of the arm 43 is provided with a clamp mechanism for seizing the sheet 42. This clamp mechanism preferably comprises a pair of jaws extending across the end of the arm. The lower jaw 56 is fixed to the arm 43 and the upper or movable jaw 57 is pivotally mounted on the fixed jaw.

Suitable springs 58 serve to hold the movable jaw 57 normally open, and the plungers 59 of suitable solenoids 61 are operatively connected with the movable jaws to close the same when the solenoids are energized. By this arrangement the arm 43 may be extended to seize the projecting end of a selected sheet, and, by moving the arm 43 backward over the top of the table 39, a portion of the sheet will be pulled from its rack and drawn over the table. Upon opening the circuit including the solenoids 61 the sheet will be released and deposited on the table.

Means, preferably integral with or forming a part of the table 39, are provided for frictionally engaging the released end of the sheet to continue the pulling-out operation. Journaled at each end of the table 39 and projecting thru an aperture 62 in the table top is a drum 63 having a series of spaced annular grooves 64. Running in these grooves are a plurality of belts 66, the upper reaches of which are arranged to rest on the top of the table 39. One of the drums 63 is driven by a motor 67 thru a suitable drive mechanism 68. As the belts are driven the upper reaches thereof slide along the top of the table. Consequently, when the sheet is de-

posited on the table it rests on the series of moving belts.

In order to effect continued forward movement of the sheet, the amount pulled out by the arm 43 is such that the frictional engagement of the sheet with the belts 66 operates to continue pulling out the sheet from its rack. At the same time, the belts 66 serve to advance the sheet along the table 39. It is thus seen that belts 66 in effect form the table top, and that they operate as a conveyor having a dual function; viz., that of continuing the pulling-out operation, and that of advancing the sheet along the elongated table 39.

As the sheet advances along the table it is inspected and cut up into rug lengths by attendants working along the passageways provided adjacent each side of the platform 24. Mounted at the discharge end of the inspection table 39 is a winder 70 for rolling up the rugs 71 into rolls. This winder is of ordinary construction and will not be described in detail.

Means are also provided for lowering the rug rolls from the platform 24 to the ground floor 2. Arranged adjacent the rear of the main frame is a third frame 72 extending vertically from the floor to a cross beam 73 positioned at a height somewhat greater than the height of the main frame. Each end of the frame 72 is supported by a truck 74 running on the rails 74', and the frame is stabilized by a grooved roller 75 at each upper end of the frame running on the guide rail 76 of the cross beam 73. A projection 77 from each side of the platform 24 serves to move the frame 72 when the main frame is moved.

Arranged on the frame 72 is a vertically operating conveyor comprising an endless belt 78 positioned at each end of the frame. Each belt runs over a pair of spaced pulleys 79, and the corresponding pulleys of the belts are interconnected by the cross shafts 80. The lower shaft of the conveyor is driven by a motor 81 thru suitable drive gears 82. Secured to each belt are a series of suitable spaced lugs or holders 83 for holding the ends of the rug rolls. As the conveyor holders move downwardly past the end of the platform 24, the workmen may insert the rolls, so that the rolls will be lowered. Other attendants working at the base of the conveyor frame 72 may remove the rolls as they are depressed.

Operation.—Considering that the racks have been filled by the hauling-in mechanism, and that the sheets first hauled in are sufficiently dry to be removed, an operator starts the drive motor 22 and moves the main frame to a position opposite a selected tier of racks. The operator now starts the reversible hoist motor 37 and raises or lowers the frame comprising the elevator platform 24.

until it is positioned opposite a selected rack. Having properly positioned the platform, the operator starts the reversible carriage motor 51 and extends the arm 43 to engage 5 the sheet 42 to be removed.

After having energized the clamp actuating solenoids 61 to seize the sheet, the operator reverses the motor 51 to retract the arm 43. With the conveyor belts 66 running, the 10 leading end of the sheet is drawn over the end of the table 39, and, after a predetermined amount of the sheet has been pulled out by the arm 43, the clamp jaws are opened to release the sheet and deposit it on the conveyor belts of the table top; this amount being such that the frictional engagement of the sheet with the belts operates to continue pulling out the sheet from its rack.

As the sheet is advanced along the table 20 39 it is inspected and cut up into rug lengths. Upon leaving the inspection table the rugs 71 are rolled up into rolls by the winder 70. Finally the rug rolls are deposited on the conveyor lugs 83 and are subsequently lowered 25 to the ground floor.

In reiteration of the advantages of my invention it is pointed out that an apparatus is provided for easily handling long, heavy and cumbersome sheets of material, such as webs of printed floor covering, as they are withdrawn from the drying racks for inspection and further treatment. The ease of handling follows from the fact that the operating station is positioned directly opposite the rack from which the sheet is being withdrawn, and that the sheet is advanced 30 along the inspection table by means which also pulls the sheet from the rack.

By positioning the operating station opposite the rack from which the sheet is being withdrawn the sheet is allowed to remain in substantially one plane, and the stresses subjected by the passing of the sheet from one level to another are avoided. By causing the 40 sheet to be withdrawn by the same means which advances it along the inspection table the number of mechanisms involved are reduced and complicated timing devices and controls are avoided. In my apparatus, 45 when the sheet is to be stopped on the inspection table it is only necessary to stop the motor 67 driving the conveyor belts 66. This stops the advance of the sheet along the table, 50 and at the same time stops the sheet from being pulled from the rack.

I claim:

1. An apparatus for handling sheets comprising a rack for holding the sheet, a conveyor opposite the rack, means for driving said conveyor, and means for pulling a portion of the sheet out of the rack and depositing it on the conveyor, the amount of the sheet pulled out by said pulling-out means 60 being such that the frictional engagement of 65

the sheet with the conveyor operates to continue pulling out the sheet.

2. An apparatus for handling sheets comprising a rack for holding the sheet, an endless belt conveyor opposite the rack, means 70 for driving said conveyor belt, and means for pulling a portion of the sheet out of the rack and depositing it on the belt, the amount of the sheet pulled out by said pulling-out means being such that the frictional engagement of the sheet with the belt operates to continue pulling out the sheet. 75

3. An apparatus for handling sheets comprising a tier of racks for holding the sheets, a frame adjustable opposite a selected rack, a conveyor on said frame, means for driving the conveyor, and means for pulling a portion of the sheet out of the rack and depositing it on the conveyor, the amount of the sheet pulled out by said pulling-out means 80 being such that the frictional engagement of the sheet with the conveyor operates to continue pulling out the sheet. 85

4. An apparatus for handling sheets comprising a tier of racks for holding the sheets, a frame adjustable opposite a selected rack, a conveyor on said frame, means for driving the conveyor, and means movably mounted on said frame for pulling a portion of the sheet out of the rack and depositing it on the conveyor, the amount of the sheet pulled out by said pulling-out means 90 being such that the frictional engagement of the sheet with the conveyor operates to continue pulling out the sheet. 95

5. An apparatus for handling sheets comprising a tier of racks for holding the sheets, a frame adjustable opposite a selected rack, a conveyor on said frame, means for driving the conveyor, an arm movably mounted on said frame, clamp mechanism on the arm adapted to seize a sheet in its rack, means for actuating the clamp mechanism, and means for moving the arm to pull a portion of the sheet out of the rack and deposit it on the conveyor, the amount of the sheet pulled out by said arm being such that the frictional engagement of the sheet with the conveyor 100 operates to continue pulling out the sheet. 105

6. An apparatus for handling sheets comprising a tier of racks for holding the sheets, a main frame arranged adjacent the end of the tier, a frame slidably arranged on the main frame for adjustment opposite a selected rack, a conveyor on said slidable frame, means for driving the conveyor, and means for pulling a portion of the sheet out of the rack and depositing it on the conveyor, the amount of the sheet pulled out by 110 said pulling-out means being such that the frictional engagement of the sheet with the conveyor 115 operates to continue pulling out the sheet. 120

7. An apparatus for handling sheets com- 125

- prising a tier of racks for holding the sheets, a main frame arranged adjacent the end of the tier, a frame slidably arranged on the main frame, hoist means mounted on the main frame for moving said slidable frame to position the same opposite a selected rack, a conveyor on said slidable frame, means for driving the conveyor, and means for pulling a portion of the sheet out of the rack and 50 depositing it on the conveyor, the amount of the sheet pulled out by said pulling-out means being such that the frictional engagement of the sheet with the conveyor operates to continue pulling out the sheet.
- 15 8. An apparatus for handling sheets comprising a plurality of tiers of racks for holding the sheets, a main frame movably arranged for adjustment opposite a selected tier, a frame slidably arranged on the main frame for adjustment opposite a selected rack, a conveyor on said slidable frame, means for driving the conveyor, and means for pulling a portion of the sheet out of the rack and depositing it on the conveyor, the 55 amount of the sheet pulled out by said pulling-out means being such that the frictional engagement of the sheet with the conveyor operates to continue pulling out the sheet.
9. An apparatus for handling sheets comprising a plurality of tiers of racks for holding the sheets, a main frame mounted for travel across the end of said tiers, means for moving the main frame to position the same opposite a selected tier, a frame slidably arranged on the main frame for adjustment opposite a selected rack, a conveyor on said slidable frame, means for driving the conveyor, and means for pulling a portion of the sheet out of the rack and depositing it on 60 the conveyor, the amount of the sheet pulled out by said pulling-out means being such that the frictional engagement of the sheet with the conveyor operates to continue pulling out the sheet.
- 45 10. An apparatus for handling sheets comprising a tier of racks for holding the sheets, a frame adjustable opposite a selected rack, an elongated table on the frame and extending in a direction longitudinally of said racks, and means for pulling the sheet out of the rack and moving it along the table.
11. An apparatus for handling sheets comprising a tier of racks for holding the sheets, a frame adjustable opposite a selected rack, an elongated table on the frame and extending in a direction longitudinally of said racks, and means including a conveyor mounted on the table for pulling the sheet out of the rack and moving it along the 65 table.
12. An apparatus for handling sheets comprising a tier of racks for holding the sheets, a frame adjustable opposite a selected rack, an elongated table on the frame and extending in a direction longitudinally of said
- racks, means for pulling a portion of the sheet out of the rack and depositing it on the table, and means frictionally engaging said sheet for pulling the remainder of the sheet from the rack and moving the sheet 70 along the table.
13. An apparatus for handling sheets comprising a tier of racks for holding the sheets, a frame adjustable opposite a selected rack, an elongated table on the frame and extending in a direction longitudinally of said racks, means for pulling the sheet out of the rack and moving it along the table, means on the frame for rolling-up the sheet as it leaves the table, and means for lowering the 75 rolls from the frame.
14. An apparatus for handling sheets comprising a movably mounted main frame, a frame slidably arranged on the main frame and along which the sheet is adapted to move, a winder on the slidable frame for rolling-up the sheet, a third frame connected for movement with the main frame and arranged adjacent said winder, and a conveyor on said third frame for lowering the rolls from the 80 85 slideable frame.
- In testimony whereof, I have hereunto set my hand.
